ALARM SYSTEM

Ellsworth D. Cook, Merchantville, N. J., assignor
to Radio Corporation of America, a corpora-
tion of Delaware

Application January 31, 1934, Serial No. 709,071

4 Claims. (Cl. 177—352)

My invention relates to alarm systems and particularly to systems of the type designed to give an audible or visible indication of the presence of an intruder in a particular protected area.

More specifically, my invention contemplates an alarm system wherein one or more oscillators are utilized, and the presence of an intruder into the protected area disturbs a predetermined balance between the oscillators, with the result that the frequency of a beat-note is changed.

Systems of the aforesaid type, heretofore known to me, have had one rather serious drawback, namely, the tendency of either or both oscillators to drift away from their assigned frequencies. Attempts have been made to overcome this difficulty, usually by providing means, responsive to weather conditions and the like, which would adjust one or both oscillators back to its predetermined frequency at a rate commensurate with the rate of occurrence of the natural phenomena. That is to say, frequently correction systems depended for their action upon very exact and nice adjustments whereby the frequency of either or both oscillators could be maintained stable.

Obviously, it is somewhat difficult to maintain a plurality of oscillators functioning with but small changes in their respective frequencies and it is, accordingly, an object of my invention to provide improved frequency drift compensating means.

In addition to the foregoing, alarm systems constructed according to the teachings of the prior art, in general, utilize correction devices which are responsive to frequency drift but the correction introduced thereby is not strictly proportional to the departure from normal of the corrected devices. It is, therefore, a further object of my invention to provide frequency-drift compensating means that shall apply a correction strictly in accordance with the amount, duration and sense of a departure from normal of the system.

The foregoing objects and other objects ancillary thereto I accomplish, not by working directly upon the output of one of the oscillators but by providing means for keeping constant the difference frequency between two oscillators in spite of the drifting of either or both of them by reason of natural causes. Specifically, I provide two oscillators having a predetermined normal frequency-difference and utilize a departure from normal of the frequency difference for the purpose of applying a correction to one of them. More particularly, I provide means for detecting

the beat frequency and impress the detected frequency, preferably 1000 cycles, after amplification, upon two filters, one a sharply tuned high-pass filter and the other a sharply tuned low-pass filter. The constants of the filters are so chosen that the characteristic curves intersect at an acute angle at a frequency corresponding to the beat frequency chosen, namely 1000 cycles.

The output from each filter is rectified and the rectified currents are applied to a balanced relay device which, in turn, through the use of a plurality of slow-closing, quick-opening relays, controls a reversible capacitor motor. The motor is coupled through a reduction gear to a vernier tuning condenser associated with one of the oscillators and, by properly choosing the polarity of the connections between the several devices mentioned, the motor may be caused to automatically adjust the tuning condenser to compensate for any drift of the beat frequency above or below the normal beat-frequency.

Further, in accordance with my invention I utilize the beat frequency, after passing through a sharply tuned band-pass filter, for the purpose of keeping open the contacts of a relay device which, when closed, complete a circuit for energizing a warning signal.

The novel features of my invention are set forth with particularity in the appended claims. The invention itself, however, both as to its organization and its method of operation, together with additional objects and advantages thereof, will best be understood from the following description of a specific embodiment when read in connection with the accompanying drawing in which

Fig. 1 is a complete diagrammatic view of an alarm system including a preferred embodiment of my invention, and

Fig. 2 shows a series of curves illustrating certain filter characteristics to which reference hereinafter will be made.

Referring now to the drawing, an alarm system constructed according to my invention includes a plurality of oscillators 1 and 3. The frequency-determining capacity of the first mentioned oscillator is constituted by the stray capacity between a ground lead, which may be an extended wire, 5, and an antenna 1, which also may be a wire extended along a wall, for example, parallel to the ground connection. The frequency of the second mentioned oscillator 3, is determined by a variable tuning condenser 9, and a variable vernier condenser 11, to which reference will later be made in detail.

Both oscillators are coupled to a link circuit including a plurality of coupling coils 13 and 14, one terminal of the circuit being conductively connected to the grid of a detector tube 17, and the other terminal leading to a common cathode connection 18. In order to prevent radiation of energy from the oscillator 1, I find it highly desirable, in certain cases, to reduce the frequency thereof to the neighborhood of 30,000 cycles per second and interpose a frequency multiplier 16 between its output circuit and the link circuit coupled to the input circuit of the detector 17. This modification is alternative and need not be illustrated in more detail since frequency multipliers, per se, are old and well known to those skilled in the art. It is to be understood, however, that following description, and the claims, are intended to cover the system either with or without the frequency multiplier since its presence in no way alters the fundamental action thereof.

In normal operation of the system the frequency of the two oscillators is so chosen that the beat produced thereby is 1000 cycles although it is, of course, to be understood that I am not limited to any particular beat frequency nor am I limited to any particular pair of frequencies for the several oscillators.

After rectification in the detector tube 17, the beat frequency is impressed upon an amplifier tube 21, through a tuned band-pass filter 23, the characteristic curve of which is shown at A in Fig. 2 of the drawing. Subsequent to amplification the beat frequency is utilized to determine the action of an alarm-circuit controlling device.

Although not limited thereto, I find it desirable to utilize for the controlling device a thermionic tube 25, such as that commercially known as a "Thyratron," hereinafter designated the relay tube. The tube in question includes, within an evacuated envelope, a control grid 27, a thermionically active cathode 29, an anode 31, and a heater 33, to which energizing potential may be applied from any commercial alternating current source such as through the utilization of a transformer 35.

Alternating anode potential is applied to the tube from the secondary of the transformer 35, over a circuit including the winding of a relay 37. The armature 39, of the relay is electrically connected to the same terminal of the transformer-secondary which is connected to the anode of the relay tube. When the relay winding is de-energized to release the armature, a circuit is completed from the said terminal through the armature, a contact member 41, the energizing winding 43, of a bell 45, or the like, the contacts and movable member of a normally closed push-button switch 47, a resistor 49, hold-in winding 51, and a condenser 54 to the other terminal of the secondary winding.

In the absence of a proper signal potential upon the grid of the relay tube, such as is applied by the positive half-cycles of the beat frequency, space current does not flow in the device. In this condition the armature 39 of the relay drops out, contacting 41, and the circuit previously described in detail is completed, which causes an alarm to be given. Condenser 54 is preferably of large capacitance to permit passage of current from the 110 volt A. C. source when the alarm is thrown in circuit by armature 39. A battery 52 is provided in shunt with condenser 54 in order that the alarm 45 may nevertheless be energized in the event of failure of the 110 volt source.

When so energized the path of the current from auxiliary source 52 is from the positive pole through, winding 51, resistor 49, push-button switch 47, winding 43 of bell 45, contact 41, armature 39 of relay 37 and back to the battery 52. With winding 51 energized the armature 39 is attracted thereto. The flux in winding 51 is sufficient to hold armature 39 over the short periods when the armature of the bell relay 43 is open so that in order to reset 39 in its normal position it is first necessary to dissipate the flux by breaking the circuit by opening the normally closed push-button switch 47.

Assuming that both oscillators are so functioning that the beat note of 1000 cycles is being impressed upon the grid of the control tube, the said tube draws sufficient current to maintain the contacts of the relay open. If, now, an intruder comes between the two wires, 7 and 8, connected to the first oscillator 1 or comes close to 20 the high potential wire 7, the frequency of the said oscillator is lowered with the result that the beat note is reduced in frequency by a definite number of cycles.

Referring now to Fig. 2 of the drawing, the curve A exemplifies the characteristics of the band-pass filter 23. From this curve it will be noted that the transmission of the filter does not vary until the beat-frequency departs from 1000 cycles by some amount in excess of one half the range covered by the flat top of the curve and that, thereafter, the attenuation is very rapid. At certain points, D and D₁, on the curve the attenuation is so great that the grid of the relay tube 25 is substantially deprived of excitation with the result that space current stops flowing therein and the relay drops out to give an alarm.

In an actual operative system constructed according to my invention, the departure from normal of the beat frequency necessary to cause an alarm, indicated by the frequency-increment Δf in the drawing, is of the order of 50 cycles, corresponding to a change in the distributed capacity to ground of the antenna 7 of the order of $\frac{1}{2}$ micromicrofarad. Since the approach of an intruder within several feet of the wire, which was disposed at a height of approximately six feet above ground or spaced the same distance from the wire 8, caused such change in the distributed capacity, the sensitivity of my improved system is ample.

In the system referred to, the oscillator 1 functions normally at a frequency in the order of 100,000 cycles per second and the oscillator 3 at 55 a frequency in the order of 99,000 cycles per second, but it is to be distinctly borne in mind that the percentage of change in frequency of the oscillator 1 occasioned by an intruder, is independent of the frequency thereof.

In order that frequency drift, occasioned by changes in potential supply, atmospheric conditions, etc., shall be compensated, I provide further means, responsive to departure from normal of the beat frequency, for adjusting the frequency 65 of the oscillator 3. To make certain that the frequency-compensating means shall not immediately counteract the effect of the change in beat frequency caused by the momentary presence of an intruder, I introduce time delay means 70 whereby compensation is deferred until a definite time interval elapses after the frequency-change has taken place. I also provide means whereby very slow changes in beat-frequency are compensated before they reach such magnitude 75

as to cause the alarm to be given. In other words, referring to Fig. 2, a departure from normal of the beat frequency by an increment, $\Delta_2 f$ less than the departure $\Delta_1 f$ necessary to give an alarm, is compensated automatically to keep the beat frequency at 1000 cycles per second irrespective of which oscillator is introducing the variation.

Specifically, referring again to Fig. 1 of the drawing, for frequency-drift compensation, I couple the input of a further audio-frequency amplifier 53 to the output circuit of the detector 17 and impress the amplified audio frequency through a high-pass filter 55 and a low-pass filter 57 upon two rectifying devices, 59 and 61, respectively. The output circuit of the high-pass filter rectifier includes a resistor 62 and one winding 63, of a balanced relay 64, the other winding 65 of the relay and a resistor 66 being included in the output circuit of the low-pass filter rectifier. A front contact 67 and a back contact 69, are associated with the armature 71 of the relay which armature, when the currents in the several windings are substantially balanced or when there is current in neither, remains in the central, open position as indicated in the drawing.

The filters are so designed as to have characteristic curves of the form of curves B and C, shown in Fig. 2, which curves intersect at 1000 cycles, and the slopes thereof at the intersection are quite steep.

The armature of the balanced relay is connected through a potential source, such as a battery 13, to the junction point 74, between the windings of a plurality of slow-closing, quick-opening relays, 75 and 77. Preferably, these relays when energized require at least one-half minute for closing but open substantially instantaneously when the windings are de-energized. The several contacts, 67 and 69, associated with the armature of the balanced relay, are connected, respectively, to the outer terminals of the slow-closing relay windings. It will be noted from an inspection of the drawing that the contact of each slow-closing relay is connected to one side of a 110 volt alternating current supply source. The other side of the source is connected to the junction point between the two windings in a reversible capacitor motor 81, one winding of the motor having a connection to the other armature, and the two windings being interconnected through a large condenser, 79. The motor drives the vernier condenser 11 through a reduction gear 82.

If the beat frequency departs from normal by a very slight amount, indicated by the point F or the point E on the curves B in Fig. 2, no correction is necessary and, in fact, such departure is insufficient, usually to cause operation of the correction means. If, however, it departs therefrom by an abnormal amount, i. e. an amount greater than $\Delta_2 f$ and less than the change caused by an intruder in the frequency of the oscillator 3, correction should take place and this correction should be continuously applied just so long as the tendency to drift persists.

To this end, the unidirectional current output from the high-pass filter rectifier 59 is normally balanced against the output from the low-pass filter 61 in the windings of the relay 64. The resistors 62 and 66, may be utilized for balancing purposes, if desired, or any other well known means may be utilized for ensuring that the

armature 71 remains in the mid-position when the output of the detector is at a frequency of 1000 cycles. The armature moves, therefore, to energize one of the slow-closing relays, only when the output current from the high-pass filter differs from that of the low-pass filter. 5

By balancing the output currents from two filters having characteristics such as shown by the curves B in Fig. 2, extreme sensitivity is obtained and compensation begins within a very short time after the beat frequency has departed from normal an amount, $\Delta_2 f$, less than the departure, $\Delta_1 f$, necessary to give an alarm. Furthermore, such compensation is continuous just as long as the tendency to drift persists, thus 15 maintaining the system always in condition such that a sudden departure from normal of the beat frequency by an amount equal to or in excess of $\Delta_1 f$ will cause the giving of an alarm. Therefore, depending upon which filter passes 20 the most current, the balanced armature will move either up or down to supply energizing potential to the lower or the upper slow-closing relay winding. I have not attempted to illustrate which winding causes the motor 81 to increase the capacity of the vernier condenser 11, nor which causes it to rotate in the opposite direction to decrease the capacity thereof, the manner in which this may be done being, of course, obvious to anyone skilled in the art. As 30 a result, however, of the connections exemplified by the drawing, any change in the beat frequency, whether the result of natural causes or occasioned by the presence of an intruder, causes the energization of one or the other of the slow-closing relays but since they close slowly, the momentary presence of an intruder occasions no correction of the oscillator although such presence does cause an alarm to be given. 35

It might be inferred from the foregoing that 40 my invention is limited by the specific relay tube 25, and relay circuits chosen for illustration. This is not the case, however, since many other equivalent devices may be utilized for the purpose of giving an alarm when the audio frequency amplifier 21 is deprived of input excitation through change in the beat frequency. Again, it might be assumed that I am limited to quite high frequencies for the oscillators 1 and 3. Such is not the case, however, since the operation 45 of my system is substantially independent of the frequencies chosen. 50

It will be apparent from the foregoing that I have provided an improved alarm system which has a number of obvious advantages, and among 55 these advantages especial attention is called to the fact that I have obviated the necessity of providing complicated circuits for keeping either or both oscillators functioning at definite frequencies. In fact, either oscillator may drift 60 away from its assigned frequency in either direction but the action of the corrective system, since the said system is controlled by the beat note, will always bring the corrected oscillator to such a frequency as to give the correct beat 65 note.

Although I have chosen certain specific preferred embodiments of my invention for purposes of illustration, many modifications thereof will be apparent to those skilled in the art. My invention, therefore, is not to be limited except insofar as is necessitated by the prior art and by the spirit of the appended claims. 70

I claim as my invention:

1. In a device of the class described, a pair of 75

oscillation generators operative to provide a beat signal of predetermined frequency, said oscillators being susceptible to normally slow variations tending to alter the frequency of said beat signal, means actuated by said beat signal for adjusting the frequency of one of said oscillators to compensate for said normal variations in the frequency of said beat signal, means for delaying the response of said last mentioned means to thereby distinguish between slow and rapid frequency variations, capacity elements connected to the other of said oscillators for producing abnormally rapid changes in the frequency of said beat signal in the presence of a foreign body when brought into predetermined relation with said capacity elements, an indicating device, and means responsive only to said abnormal changes in the frequency of said beat signal for actuating said indicating device.

2. In a device of the character described, means for generating a signal current of predetermined frequency, said generating means being subject to normally slow frequency variations which tend to alter said predetermined frequency, an alarm, means responsive to currents of a range of frequencies including said predetermined frequency for maintaining said alarm in responsive condition, means responsive to the presence of foreign bodies for changing the frequency of said currents of predetermined frequency to thereby actuate said alarm responsive means, means for compensating for said normally slow frequency variations and actuated by said variations to thereby maintain said predetermined frequency, and means which is slow to operate but quick to release for delaying the action of said compensating means so that the said frequency compensating means will only respond to said normally slow variations whereby said compensation means is slowly operated to maintain said signal current substantially at said predetermined frequency and quickly released after said compensation has been effected.

3. In a device of the character described, a pair of oscillators for generating a beat frequency current, said oscillators being subject to normally slow frequency variations, an alarm, means responsive to said beat frequency current for maintaining said alarm in responsive condition, means responsive to the presence of foreign bodies connected to one of said oscillators for changing said beat frequency and thereby actuating said alarm, means for compensating for said normally slow frequency variations and actuated by said variations to thereby maintain said beat frequency, and means which is slow to operate but quick to release for delaying the action of said compensating means so that said compensating means will only respond to said normally slow variations whereby said compensation means is slowly operated to maintain said beat frequency current and quickly released after said compensation has been effected.

4. In an alarm system, a pair of oscillators for generating a beat frequency current, said beat frequency being subject to normally slow frequency variations, means for compensating for said normally slow variations and actuated by said variations, means which is slow to operate but quick to release for delaying the operation of said compensating means so that said means are unresponsive to abnormally rapid frequency changes whereby said compensation means is slowly operated to maintain said beat frequency current free from said slow variations and whereby said compensation means is quickly released after said compensation has been effected, an alarm, means responsive to said beat frequency currents for maintaining said alarm in responsive condition, and means responsive to the presence of a foreign body for causing abnormally rapid variations in said beat frequency to thereby actuate said alarm.

ELLSWORTH D. COOK.
